[57] ABSTRACT

An infra-red heat generator having a generally cup-shaped body which has an open front end. A perforated diffuser extends across the body lying in a plane parallel to and spaced from the open front end. The diffuser defines a mixing plenum in the rear of the body behind the diffuser. There is an inlet into the

plenum for a combustible gas mixture. The percentage of open area of the diffuser is such that during operation a positive pressure is maintained in the plenum. The diffuser is held in place by a spacer which fits into the open end of the body. A multi-layer primary screen lies across the open end of the body. The layers of the primary screen are welded to each other in an orientation with the elements of each layer overlying, in part, the openings of the adjacent layer and the layers are contiguous throughout. The edges of the primary screen lie against the front edges of the generator body which define its open end and the center of the primary screen is convex relative to its edges. The elements of the screen layers are deformed against each other at their crossing points to provide substantial areas of surface contact therebetween. A centrally convex reverberator grid is positioned in front of the primary screen by a spacer that extends between the edges of the screen and the grid. The diffuser, primary screen, grid and spacer are all held in position by a cap which has an inwardly directed lip overlying the edges of the grid and a main flange which telescopes over the front of the generator body and extends around the edges of the primary screen. A retainer is wedged between the outer surface of the body and the main flange of the cap to hold the parts in assembled position.

INFRA-RED HEATER

BACKGROUND OF THE INVENTION

Portable, gas-fired radiant heat generators usually are designed for assembly onto pressurized containers of propane or butane gas. Such heaters, for the most part, have been unnecessarily complex, both in manufacturing and assembly, and have embodied design faults which necessitated the utilization of expensive heat resistant gaskets, assembly means such as screws, nuts, bolts, clips, and the like, and frequently have been so poorly designed as to require extremely careful handling in order to prevent flashbacks of the burning gases and the loss of efficiency.

It is, therefore, the principal object of the instant invention to provide a gas-fired infra-red heat generator which consists of a small number of parts, each simple to manufacture, and that is so designed as to provide for simplicity of assembly and consequent lightweight and low cost.

It is another object of the instant invention to provide a gas-fired infra-red heat generator not only so designed to reduce its cost by simplifying its assembly and the number of parts involved, but also to incorporate design considerations by which the possibility of flashback is substantially eliminated, by which the transfer of heat produced is controlled to improve its efficiency and yet which is lightweight, inexpensive to manufacture and effective for the purpose designed.

It is yet another object of the instant invention to provide a small, lightweight infra-red heat generator which is particularly adapted for use in the removal of paint, the softening of adhesives such as those used to fix vinyl or asphalt floor tiles and the softening of such tiles themselves to facilitate their laying and/or removal.

Another important object of the instant invention is to provide a portable infra-red heat generator which is simple to assemble but which substantially precludes dis-assembly by an ordinary user thus to substantially eliminate the problems which would result upon improper re-assembly of the generator by a non-trained person.

A still further object of the instant invention is to provide an infra-red heat generator having a superior primary or combustion screen so designed as to substantially eliminate flashback, to achieve radiation temperatures rapidly, to reach and remain at substantially uniform temperature throughout its over-all area and to enable the generator to operate efficiently in almost any position.

BRIEF DESCRIPTION OF THE DRAWINGS

FIG. 1 is a vertical sectional view of a generator embodying the invention;

FIG. 2 is a view in front elevation taken at the right side of FIG. 1, with parts broken away;

FIG. 3 is a vertical sectional view taken along line 3-3 of FIG. 1;

FIG. 4 is a vertical sectional view taken along line 4-4 of FIG. 1;

FIG. 5 is an isometric view of the primary screen employed in a generator according to the invention;

FIG. 6 is a fragmentary view, partly in section and partly in elevation, illustrating a modification of the assembly means of a generator embodying the invention;

FIG. 7 is a view similar to FIG. 1, but of another embodiment of the invention;

FIG. 8 is a detailed isometric view of a modified form of diffuser according to the invention;

FIG. 9 is a fragmentary view in elevation of a small portion of a primary screen having two layers according to the invention, shown on an enlarged scale; and

FIG. 10 is a comparative view on a greatly enlarged scale of fragments of screen elements at their crossing points as in an old screen and as in a screen shaped according to the invention.

DESCRIPTION OF THE PREFERRED EMBODIMENTS

A radiant heat generator embodying the invention has a generally cup-shaped body indicated by the reference number 10 which has an open front end. An inlet pipe 11 for a mixture of combustible gases is connected to the rear portion of the body 10. The pipe 11 comprises an air induction venturi (not shown) and is connected to a pressurized gas container. Gas from the container is fed through the venturi by which air is inspirated with the gas and then the combustible mixture flows through the inlet pipe 11 into a charging plenum 12 defined by the rear and walls of the body 10 and a diffuser 13.

The perforated diffuser 13 extends across the body 10 and is held in place by a spacer 14 which fits within the open end of the body 10. In this embodiment of the invention the spacer 14 is a separate piece, being formed as a split-ring which holds the diffuser at a fixed distance from the edge of the body 10 which defines its open end 13. In a generator according to the invention the diffuser 13 has a percentage of open area selected to control the rate of flow of the combustible mixture through the perforations from the plenum 12 forwardly at a rate such that a positive pressure is maintained in the plenum 12 and that the flow rate of the gases through the perforations will be in excess of the flame propagation speed of the gases to be combusted thus to aid in the substantial elimination of flashback of the burning gases into the chamber 12.

Contrary to the teachings of some prior art workers, I have found that for infra-red heat generators to be employed with butane and propane gases from regulated pressurized containers, the percentage of open area in the diffuser should not be above 30 percent nor below 10 percent and preferably should be in the order of 20-25 percent. In a generator according to the invention, operating on liquified gas, optimum operation is achieved with an open area of 23 percent.

The front edge of the spacer 14 lies substantially in the same plane as the front circular end of the walls of the body 10 and preferably is fabricated from at least slightly resilient material so that it can be easily inserted into the open end of the body 10 and, upon expansion, will frictionally engage the inner surface of the wall of the body 10, securely retaining the diffuser plate 13 in place.

A convexly crowned, multi-layer, primary screen 15 consisting of at least two layers of screening 15a and 15b has a size such that its edge overlies the edge or end of the body 10 and may extend outwardly slightly beyond the edge of the body 10. The two layers of screen 15a and 15b preferably are shifted relative to each other so that the screen elements of each layer overlie

in part the openings between the elements of the other layer, as is shown in FIG. 9. Such overlapping creates a tortuous path for the passage of gas through the two layers of the screen 15. The two layers 15a and 15b are welded together, as indicated by the reference number 16, to maintain them in the overlapped orientation and to hold them contiguous to each other throughout their surfaces. After the two layers 15a and 15b are oriented as described and welded together, they are convexly crowned in a pair of coining dies which are closed to such spacing that the individual screen elements, i.e., the wires, are deformed against each other to greatly increase their contact throughout their surfaces. As can be seen by comparing the two parts of FIG. 10, an ordinary screen, (indicated by the legend "Old") has point contact only between the surfaces of its crossing wires 17 and 18. In sharp contrast, when the screens 15a and 15b are coined, the individual elements or wires are deformed so that each contact between touching wires 19 and 20 becomes a surface 21. The resulting tremendous increase in surface contact between the elements of each layer 15a or 15b and, similarly, between the elements of layer 15a and those of 15b, provides for rapid and uniform heat transfer between the screen layers 15a and 15b. In one embodiment of the invention, for example, each layer has a nominal thickness of .040 inch and the two layers are coined to a combined thickness of .060 - .065 inch.

The convex crowning of the screen 15 is also accomplished at the time of coining and establishes a bias forwardly so that as the screen 15 expands upon increase in its temperature, it cannot bow in a concave direction, thus preventing it from decreasing the space in front of the diffuser plate 13 and eliminating any possibility that it might even contact the diffuser plate 13.

The exposure of the elements of the inner screen layer 15b between the elements of the forward layer 15a, resulting from the staggered orientation illustrated in FIG. 9, has the added advantage of increasing the area of the screen 15 which is visibly exposed when raised to infra-red generating temperature.

A second spacer 22 lies against the edges of the screen 15 and extends forwardly to space and position a reverberator grid 23 that is fabricated from an open mesh screen and which is also crowned in its central portion on a curvature approximately the same as that of the coined screen 15. Preferably the grid 23 also is coined to deform its elements against each other in order to create surfaces of contact between them, as illustrated in FIG. 10. The edges of the grid 23 overlie the spacer 22.

The entire assembly so far described is retained on and in the end of the body 10 by a cap 24. The cap 24 has an inwardly directed lip 25 and a backwardly extending flange 26. The lip 25 has an open diameter substantially equal to the inside diameter of the spacer 22 and overlies and is positioned against the edge of the reverberator grid 23. The flange 26 has an inside diameter in which the spacer 22 makes a relatively tight friction fit and it is large enough to extend backwardly circumjacent the edge of the body 10 toward the rear of the body 10. The diameter of the flange 26 of the cap 24 is such that an annular space remains between the inner side of the flange 26 and the outer surface of the front portion of the body 10. In the embodiment of the invention illustrated in FIGS. 1-5, inclusive, with par-

ticular reference to FIG. 1, an annular locking ring 27 is wedged in this annular space between the flange 26 and the outer surface of the body 10.

In assembling a heater as described above, the diffuser plate 13 is dropped into the open end of the body 10 and the first spacer 14 is then forced in to hold the diffuser plate 14 in place. The reverberator grid 23 is then put into the open cap 24, lying against its lip 25 and the second spacer 22 then forced into the cap 24 to retain the edge of the grid 23 against the inner side of the lip 25. The primary screen 15 is then positioned against the edge of the body 10 and the edge surface of the spacer 14, and the cap 24 (with the spacer 22 and reverberator grid 23) is telescoped over the open end 15 of the body 10. The locking ring 27 is then wedged forwardly from the back to tightly retain the elements in assembled position.

FIG. 6 shows a modified structure for assembling a generator embodying the invention in which a wire-like locking ring 28 is used instead of the annular, flat, locking ring 27 shown in FIG. 1. After assembling the diffuser 13, spacer 14, and screen 15 in the body 10 and the grid 22 in the cap 24, the cap 24 is telescoped over the body 10, as described above. The wire locking ring 28 is then forced into the annular space between the flange 26 of the cap 24. The flange 26 is staked at several points around its periphery, for example, as indicated by the reference numbers 29. The staking retains the locking ring 28 in place and, therefore, fixes the entire assembly as illustrated in FIG. 6, in a permanent manner.

In the embodiment of the invention illustrated in FIGS. 7 and 8 a generator according to the invention comprises an open ended body 30 to which a combustible mixture of gas and air is fed from an inlet pipe 31. The inlet pipe 31 leads into the side of the body 10 and the rear portion of the body 10 functions as a plenum 32, the forward margin of which is defined by a transversely extending diffuser 33. In this embodiment of the invention the diffuser 33 and its spacer are integral, a circular flange 34 of the diffuser 33 serving to space its main web rearwardly of the open end of the body 30. The spacer flange 34 of the diffuser 33 has an outwardly directed lip 34a which fits against the forward edge of the body 10 defining its open end. The spacer flange 34 of this embodiment of the invention functions identically with the first spacer ring 14 of the embodiments illustrated in FIGS. 1-5 and 6.

As in the earlier described embodiments of the invention a multi-layer primary screen 35, identical with the screen 15 of the earlier embodiments, is positioned across the open end of the body 10 and, similarly, two layers 35a and 35b of the screen 35 are retained in their properly oriented and contiguous relationship (as described above) by a center weld 36. A second spacer 37 and a reverberator grid 38 are positioned on the open end of the body 10 by a lipped cap 39 and a locking ring 40 similar to those of the earlier described embodiments.

FIG. 7 also illustrates the utilization of a reflector 41 designed to concentrate and, to a certain extent, to focus, the infra-red energy emitted from the primary screen 35 and the reverberator 38. The reflector 41 has a flared section 42 and a circular rim 43 which fits closely circumjacent the outer surface of the retainer cap 39. The reflector 41 is permanently mounted on the generator by the use of a plurality of inwardly ex-

tending drive pins 44 which extend through the circular rim 43 of the reflector 41 and through the cap 39 into the locking ring 40.

Thus, although the wedging of the locking ring 40 into the position illustrated permanently assembles the elements of the generator against ready dis-assembly, the drive pins 44 which mount the reflector 41 render dis-assembly of the parts even more difficult.

A generator according to the invention, as illustrated in FIG. 7 operating with regulated entry pressure of the air/gas mixture and a ratio of approximately 10 parts of air to one part of propane, has been found to be extremely effective as a hand held tool for the purpose of softening paint to expedite its removal, softening adhesives which retain vinyl and asphalt floor tiles, and the like, and softening the tiles themselves in order to facilitate their cutting and placement. The temperature of the front layer 15a of the primary screen 15 quickly reaches the level of about 1,600° F while the inner layer 15b of the screen remains below 1,000° F due to the cooling effect of the gaseous mixture flowing through the fuel diffuser 13 and thence through the layers of the primary screen 15. It is believed that these temperatures are reached and maintained by reason of the direct metal to metal contact between the edges of the screen 15 and the spacers 14 or 34, the spacers 22 and 37 and the reverberator grids 17 and 38. Under these conditions the reverberator grid also reaches and remains at a temperature of 1,600° F.

Contrary to previous teachings such as those in Honger U.S. Pat. Nos. 3,021,893 and 3,129,749, I have found that the intimate contact throughout their surfaces of the two layers 15a and 15b of the primary screen 15, particularly when deformed to provide surfaces for heat transfer as illustrated in FIG. 10, results in a more nearly perfectly uniform operating temperature across the outer faces of the overlapped primary screen layers 15a and 15b and yet establishes the substantial temperature differential between the inner screen layer 15b and the front screen layer 15a. I believe that this results from the transfer of heat from the inner screen layer 15b to the mixture of air and fuel delivered to the space behind the primary screen layer 15b through the apertures in the diffuser 13 or 33.

Substantial elimination of all tendency of a generator embodying the invention to "flashback" is believed to result from the establishment of three different pressure zones. The pressure in the plenum behind the diffuser plate 13 or 33 is substantially higher than the pressure in the zone in front of the diffuser plate 13 or 33 between it and the primary screen 15, by reason of the restrictions of the orifices in the diffuser 13 or 33. Because the air/gas mixture then flows through the tortuous passages between the elements of the primary screen layers as illustrated in FIG. 9, the third pressure zone in front of the screen 15 in the area into which the gasses are combusted is lower than the pressure in the space between the diffuser 13 or 33 and its respective screen 15. Combustion of the gases actually takes place in the interstices between the elements of the two screen layers 15a and 15b and the outer 180° cylindrical surfaces of the screen elements rapidly reach infrared emitting temperature so that they generate and direct the maximum amount of free radiant energy at the reverberator grid. The reverberator grid reaches operating temperature in a very short span of time, say in the order of a few seconds.

The edge surfaces of both the reverberator grid and the primary screen which are in contact with the spacer and the body deliver a portion of the heat energy to the body 10 and, therefore, to the diffuser 13 or 33 and that heat is in turn absorbed to a large degree by the incoming cold combustible gases which flow through the perforations of the diffuser 13 or 33. This results in heating and expanding the incoming combustible gases and cooling the surfaces of the generator body 10.

10 In the embodiment of the invention illustrated in FIG. 7, heat transferred to the spacer from the reverberator grid and primary screen also is transferred to the rim and the conical section of the reflector whence it is radiated into the area around the reflector which further cools the body 10.

An additional desirable aspect of a generator embodying the invention results from the fact that no positive mounting means such as pins, bolts, screws, or rivets are necessary to fix the position of the edges of the primary screens 15 or the reverberator grids 23 or 38. 20 Thus, particularly because both of them are crowned forwardly as described above, as they expand upon increase in their temperatures, there is no tendency for either to be buckled or malformed. Not only is the center portion free to move forwardly as it increases in temperature and expands but also the edges are not prevented from moving outwardly as a result of expansion under high temperature.

What I claim is:

30 1. A gas-fired infra-red heat generator comprising, in combination,
an open-ended, cup-shaped body defining a plenum,
a combustible fuel mixture inlet into said plenum,
a perforated diffuser extending across said body and defining the front margin of said plenum,
a first spacer fitting within the open end of said body for holding said diffuser in position,
a primary screen having interwoven metal elements, 35
said primary screen extending across the open end of said body and having a size slightly larger than and extending outwardly beyond the end of said body, said primary screen being crowned convex in its central area,
a second spacer having an inner diameter substantially equal to the open end of said body and positioned against the margin of said primary screen, 40
a reverberator grid of substantially the same diameter as the outer diameter of said second spacer,
the margins of said grid and said primary screen being in direct contact with opposite sides of said second spacer,
a cap having an inwardly directed lip engaging the margin of said grid and a perimeter flange extending around and beyond said second spacer and spaced from the outer surface of said body, 45
and a means comprising a locking ring positioned between the inner surface of said cap wall and the outer surface of said body for holding said cap on said body and said diffuser screen, grid and spacers in assembled relationship.

50 2. A generator according to claim 1 in which the first spacer is an annular flange integral with the diffuser.

55 3. A generator according to claim 1 in which the interwoven elements of the primary screen are deformed at their crossing points for establishing surface contacts between the elements.

4. A generator according to claim 1 in which the primary screen has at least two layers that are contiguous throughout their surfaces.

5. A generator according to claim 4 in which the elements of each layer of said screen overlap the interstices of an adjacent layer.

6. A generator according to claim 1 in which the diffuser has an open area in the range of more than 10 percent and less than 30 percent.

7. A generator according to claim 6 in which the open area of the diffuser is in the range of 20 to 25 per-

cent.

8. A generator according to claim 1 having a flared reflector which comprises a flange fitting closely circumjacent the flange of the cap and is secured thereto.

9. A generator according to claim 1 in which the reverberator grid is a woven metal mesh and the elements thereof are deformed at their crossing points for establishing surface contacts between the elements.
